RAYMOND H. OLLEY, OF SYRACUSE, NEW YORK, ASSIGNOR TO CROUSE-HINDS COMPANY, OF SYRACUSE, NEW YORK, A CORPORATION OF NEW YORK.

PANEL-BOARD CABINET.

1,172,826.

Specification of Letters Patent. Patented Feb. 22, 1916.

Application filed May 6, 1910, Serial No. 559,711. Renewed February 4, 1911. Serial No. 606,642.

To all whom it may concern:

Be it known that I, RAYMOND H. OLLEY, a citizen of the United States, residing at Syracuse, in the county of Onondaga and 5 State of New York, have invented certain new and useful Improvements in Panel-Board Cabinets, of which the following is a specification.

This invention relates to improvements in 10 panel board cabinets, designed for use in housing and protecting the electric distributing parts, and the invention relates particularly to that class of panel board work which is inclosed in a box setting flush with 15 or on the surface of the wall of a building.

The object of the invention is to provide 20 a simple, strong and serviceable cabinet of the class, which is arranged with a compartment for containing the switches or cut-outs, and which is surrounded by a wall for providing a closed gutter, between the cut-outs and the feed and distributing wires. A further object is to provide a number of 25 novel and coöperating parts for adjustably securing the panel board and the gutter walls to the inner side of the cabinet. The said securing means arranged at the several corners of the panel board, and each consisting of a plurality of clamping members, 30 capable of being readily and quickly applied or removed. Each set of clamping parts arranged for independently applying, adjusting or removing, and the several members comprising each set also capable of 35 adjustment in relation to each other.

A particular object of the invention is to 40 provide a series of clamping sets or parts, by the use of which the panel board base and the gutter walls require no perforations or other special treatment, in order to prepare the said parts for installation in the cabinet or box. And a further object is to provide 45 supporting devices for panel boards comprising but few parts, of novel and simple construction and arrangement, which may be produced at slight expense and assembled and applied with a minimum of skilled labor.

To this end the invention consists of the 50 novel construction and arrangement of the parts as set forth in the detail description

which follows, as illustrated by the accompanying drawing, and as particularly pointed out in the appended claims.

In the accompanying drawing, Figure 1 55 is a front view of a panel board cabinet, partly in elevation and partly in section, showing the construction, location and arrangement of the several parts of the invention. Fig. 2 is a sectional view taken on line 60 2-2 of Fig. 1, showing the manner of applying the adjustable clamping members. Figs. 3 and 4 are respectively a top plan and a front elevation of the inner clamping member. Figs. 5 and 6 are similar views of 65 the main corner bracket and support. Figs. 7 and 8 are respectively an end and a side view of the outer clamping member. Fig. 9 is a sectional view, showing modified form 70 of clamping parts, for use in securing panel members in the same plane.

Similar characters of reference designate 75 corresponding parts throughout the several views.

In the drawings, the cabinet proper 80 consists of a box, open at one face and comprising side walls 2, end walls 3, a bottom 4, and a mat or cover 5 which is secured to the open face of the cabinet by screws 6. To gain access to the interior of the cabinet an 85 opening, square or rectangular, is formed in the center of the mat 5, and this opening is closed by a door 7 which is hinged to the mat, as at 8-8. On the bottom of the cabinet opposite the central opening in the 90 mat is disposed a panel board or base 9. The panel board 9 preferably corresponds in form to the cabinet or box, and may have a larger or smaller area than the opening in the mat 5. The panel base 9, in the present 95 device is placed directly against the flat bottom or back 4 of the box. Against each side and end of the panel board is disposed a relatively narrow strip of suitable material comprising the inner wall 10-10 and 11-11. These strips are set on edge, and at right angles to the plane of the board 9. The lower or inner edges of the strips 10 and 11 preferably bear against the bottom 4 of the box, while their upper or outer 100 edges preferably approach substantially to the underside of the mat 5. Under this ar-

angement a closed space or gutter 12 is provided and extends all around the panel board in which the feed and distributing wires and other connections may be conveniently installed.

To hold the parts comprising the panel board base and the strips which form the inner walls of the gutter in place, I provide a series of coöperating clamping parts, and 10 dispose the same within the metallic box, one set of which is arranged at each corner of the panel board. The clamps for each corner consist of two oppositely formed brackets 13 and 14, and a third angular 15 member 15. The brackets 13 are substantially L-shaped and are disposed in diagonal position out-side of the corners of the panel board, and are secured to the bottom 4 of the cabinet by screws 16, which pass through 20 slots 17 formed in the foot or flange of each bracket, and thence through threaded holes 18 in the bottom 4. The upright arm of each of the brackets 13 is formed at right angles to the flange or foot, and this portion 25 is cast or formed into a right angle groove or corrugation which faces away from the flange and which receives the corner of the panel board 9. When the four brackets 13 are placed against the corners of the panel 30 board and the screws 16 are tightened up, the board will be held from endwise or side-wise movement, and by reason of the slots 17, the board may be adjusted so as to coincide with the opening in the mat 5. The 35 inner bracket 14 has one end formed into a flange 14', which rests upon the face side of the panel board, while the opposite end of this bracket is formed into a right angle groove or corrugation, which faces the said 40 flange and thus corresponds to, and is capable of interlocking with, the groove in the bracket 13. The brackets or inner corner pieces 14 are positioned inside of the panel board inclosure, and are arranged to over- 45 lap the adjacent ends of the strips 10 and 11 and the edges of the upright portions or standards of the brackets 13 serve to prevent endwise movement of the lining strips too far into the clamping means and act as gages 50 or guides by which the position of the lining strips can be determined when being placed in position. Hence, said edges of the standards coöperate with the other parts of the clamping means to position the lining 55 strips, although one or both end edges of the lining strips may not engage the edges of the standard. In Fig. 1, the lining strips are shown as slightly spaced apart from the upright portions of the standards; and in 60 Fig. 9, the lining strips are shown as engaging at their end edges the upright portions of the standard. By referring to Fig. 1, it will be seen that the strips 10 and 11 are each shorter than the ends and sides of the panel 65 board, and are set relatively to the board,

so as to leave an opening or gap at each corner. The brackets 14 when placed in position as shown in Fig. 1, close the gaps at the corners and serve to hold the panel board and the strips in true position. The brackets 13 and 14 of each corner set are then secured together by means of a screw 19, which passes through a slot 20 in bracket 14, and thence through a threaded hole 21 in the bracket 13. When the screws 16 and 19 are tightened up the panel board 9 will be held from movement in any direction.

To hold the gutter frame parts 10 and 11 truly at right angles to the panel board and also tightly against the outer edges of said 80 board, a clamping member 15 is disposed at each corner of the panel board inclosure, as shown in Fig. 1, in such manner that the lateral edges of the said members overlap the outer sides of the adjacent ends of parts 85 10 and 11. Each clamping member 15 is held in place by means of a screw 22, which passes through a slot 23, in the bracket 14, thence through a perforation 24 in the bracket 13, and thence into a threaded hole 90 25 in the member 15. The tightening up of the screws 22 will draw and hold the brackets 14 and members 15 tightly against the opposite sides of the gutter strips 10 and 11, and thus securely hold the latter in true position relatively to the panel board. The slots 95 20 and 23 in the brackets 14 are provided for affording adjustment of said bracket toward or away from the bottom of the box, to take care of the panel bases 9, which may 100 be of varying thickness. The perforations 24 in the brackets 13 should be larger than the screws 22, for allowing the parts to be securely clamped to the wall strips without danger of cramping the said parts and rendering the clamps imperfect.

Fig. 9 illustrates a modified arrangement of the panel members, in which is shown two sections of a panel base 9', and also two of the side strips 10' of the same construction as shown in Fig. 1, which are so joined as to form a continuation one with the other in the same plane. This construction is generally followed where cabinets are of such length and width that additional supports are required for both the panel base and inner gutter walls other than those placed at the corners. Under this modified arrangement the corner supports are usually the same as shown in Fig. 1, but some additional supports are necessary at the sides or ends or both intermediate the corners, where the joints between the base sections and the wall strips occur. In order to properly secure and hold the panel parts in place, as 115 last described, I employ plain outer and inner brackets 13' and 14'' and also an outer clamping part which consists of a flat plate 15' all of which parts are drawn and held in clamping position by a screw 22'. 120 130

The panel board cabinets or boxes are usually made up by the manufacturer and shipped to the building contractors in advance of the installation of the electric parts. The mats or trim for the cabinets are made and fitted to the boxes and then removed and laid aside until the boxes are embedded in the walls of the building. After the building is completed, the panel boards, gutter walls, and the securing devices for these parts, as well as, the electric fittings are placed in position in the cabinet, and the connections between the panel board fittings and the feed and distributing wires are made, after which the mat or cover is placed in position to close the open side of the cabinet.

One particular advantage claimed for the present invention is that, the slate slabs which comprise the panel board base and the gutter walls, as well as, the corner clamping sets may be finished and shipped by the factory to the place of installation in "knock-down" condition. In this manner much time is saved in the assembling and packing of the parts, and besides there is little or no danger of any of the parts becoming broken or injured in transit. Heretofore under many of the older methods of constructing and arranging the panel board cabinets, the base and gutter walls and also the supporting devices, owing to the complicated nature and arrangement of the same, had to be assembled and set in the cabinets by skilled workmen before the goods were shipped to the place of installation. Under the construction and arrangement of the present device, none of the parts comprising the panel board or gutter walls require any perforations or other special work to prepare them for installing in the cabinets. The panel board bases may vary slightly in length, width and thickness and still be readily set in place without requiring any further cutting or change, as all such discrepancies and inaccuracies are taken care of by the adjustable arrangement of the clamping parts. All of the supporting and clamping parts are made and arranged in the simplest form, and the whole complement of parts comprising the cabinet and electric fittings are capable of being assembled and installed in a ready and quick manner, by persons of ordinary skill.

Having thus described my invention, what I claim as new and desire to secure by Letters Patent, is—

1. The combination of a panel board, lining strips and means for securing the panel board and lining strips in position including a supporting member, a clamping member carried by the supporting member and having wings for engaging the inner faces of adjoining lining strips, and a web connecting the wings at the lower ends thereof

and bearing upon the face of the base of the panel board, means engaging the outer faces of the lining strips and coacting with the clamping member to hold said strips, and means for clamping said member, substantially as and for the purpose described. 70

2. The combination of a panel board, lining strips, and means for securing the panel board and lining strips in position, said means including a supporting member, a 75 clamping member supported by the supporting member and having a clamping face for engaging the front face of the panel board and holding the panel board in position, and clamping faces engaging the inner faces of lining strips, a second clamping member coacting with the first clamping member and engaging the outer faces of the lining strips, means connecting one clamping member and the supporting member, the clamping members being movable relatively to each other and to the supporting member, and means for moving the clamping members relatively to each other and to the supporting member, said means 80 operating to draw the clamping members toward each other when operated in one direction, substantially as and for the purpose described. 85

3. The combination of a panel board, lining strips and means for securing the panel board and lining strips in position, said means including a supporting member, a clamping member carried by the supporting member and having faces engaging the inner faces of the lining strips, a second clamping member coacting with the first clamping member and engaging the outer faces of the lining strips the clamping members being movable relatively to each other 90 and to the support, means for moving one clamping member relatively to the support and the other clamping member, and means for drawing the clamping members toward each other relatively to the support, substantially as and for the purpose set forth. 100

4. The combination of a panel board and cabinet therefor, and lining strips, supports for the panel board, the panel board lying flat on the bottom of the cabinet, each support comprising a member secured to the bottom of the cabinet, inner and outer clamping members, engaging opposite faces of contiguous lining strips, the inner clamping member having a clamping face for frictionally engaging the face of the panel board and holding the same flat against the bottom of the cabinet and the inner clamping member being secured to the first-mentioned member, and means for drawing the 115 clamping members together, substantially as and for the purpose described. 120

5. The combination of a panel board and cabinet therefor, and lining strips, supports for the panel board, each comprising a stand- 125

- ard secured to the bottom of the cabinet and extending upwardly between the ends of contiguous lining strips, inner and outer clamping members arranged on opposite sides of the standard and engaging opposite faces of said strips, means for securing the inner member to the standard, and means for drawing the inner and the outer members toward each other, substantially as and for the purpose specified. 5
6. The combination of a panel board and cabinet therefor, and lining strips, the panel board resting on the bottom of the cabinet, supports for the panel board, each comprising a standard secured to the bottom of the cabinet, and extending between the ends of contiguous lining strips, inner and outer clamping members arranged on opposite sides of the standard and engaging opposite faces of the contiguous lining strips, the inner clamping member having a clamping face for frictionally engaging the face of the panel board and holding the same flat against the bottom of the cabinet, means 10 for securing the inner member to the standard, and means for drawing the inner and outer members toward each other, substantially as and for the purpose set forth. 15
7. The combination of a panel board and cabinet therefor, lining strips, corner supports, each comprising a standard secured to the bottom of the cabinet and extending between the ends of contiguous lining strips and engaging the end faces thereof, a clamping member supported by the standard and coacting with the lining strips, and means for connecting the clamping member and the standard, substantially as and for the purpose described. 20
8. The combination of a panel board and cabinet therefor, and lining strips, the panel board lying flat on the bottom of the cabinet, supports for the panel board, each comprising a standard secured to the bottom of the cabinet, inner and outer clamping members supported by, and arranged on opposite sides of the standard and engaging opposite faces of contiguous lining strips, and means for drawing such members together, substantially as and for the purpose specified. 25
9. The combination of a panel board and cabinet therefor, and lining strips, the panel board lying flat on the bottom of the cabinet, supports for the panel board, each comprising a standard secured to the bottom of the cabinet and extending between the ends of contiguous lining strips, and engaging the end faces thereof, inner and outer clamping members arranged on opposite sides of the standard and engaging opposite faces of the lining strips, the inner clamping member having a clamping face for frictionally engaging the face of the panel board and holding the panel board flat against the bottom of the cabinet and said inner clamping member being secured to the standard, and 30
- flat against the bottom of the cabinet, and the inner clamping member being secured to the standard and means for drawing the outer clamping member toward the inner, substantially as and for the purpose set forth. 35
10. The combination of a panel board, lining strips, and a support having means for engaging the panel board and the lining strips, and holding the same in position and also means extending between the ends of contiguous lining strips and engaging the end edges of such strips, substantially as and for the purpose set forth. 40
11. The combination of a panel board, lining strips, and means for supporting the panel board and lining strips, said means comprising a support, clamping members for engaging inner and outer faces of the lining strips, means for securing one of said members to the support and one of the members having a clamping action toward the panel board and being provided with a face for frictionally engaging the upper face of the panel board, and the support including a part extending between opposing edges of the strips and between the clamping members, and means for clamping said members in position, said means being located entirely external of the panel board so that the panel board is not perforated by the fastening means, substantially as and for the purpose described. 45
12. The combination of a panel board and cabinet therefor including wall strips, lining strips, corner pieces, each comprising a standard angular in cross section secured to the bottom of the cabinet and engaging the edges of the strips of the cabinet forming a corner, an angular clamping member supported by the standard and coacting with the lining strips, and a flange at one end connecting the sides of the angular portion of said clamping member, the flange frictionally engaging the face of the panel board, substantially as and for the purpose specified. 50
13. The combination of a panel board and cabinet therefor, lining strips, the panel board lying flat on the bottom of the cabinet, corner supports for the panel board each comprising a standard secured to the bottom of the cabinet and having an angular part fitting the corner of the cabinet, inner and outer angular clamping members arranged in opposite sides of the standard and engaging opposite faces of the contiguous lining strips, the inner clamping member having a flange at one end connecting the sides of the angular portion of said inner clamping member and frictionally engaging the face of the panel board and holding the panel board flat against the bottom of the cabinet and said inner clamping member being secured to the standard, and 55

means for drawing the outer clamping member toward the inner, substantially as and for the purpose set forth.

14. The combination with a panel board and a cabinet therefor, of a plurality of supports for the panel board, each support comprising a member capable of being adjustably secured to the cabinet and adapted to engage a corner of the panel board, a second member arranged for engaging the face of the panel board and also for interlocking with said first member adjacent the corner of the panel board, and a third member adapted to coöperate with said second member for clamping and holding parts of a gutter wall against the edges of the panel board, means for adjustably connecting the first and second member, and means for adjustably connecting the second and third member.

15. The combination with a cabinet and a panel board therein, said panel board surrounded by a gutter formed by a series of wall-strips arranged at each side and end of said board, of a plurality of supports for said panel board and said wall strips, each support comprising a main bracket capable of being adjustably secured to the inner wall of the cabinet and arranged to receive a corner of said board, an inner bracket having a flange for engaging the face of said board for holding the same against the cabinet, and having an angular portion adapted to interlock with a like portion of the main bracket and also to overlap the adjacent ends of the wall strips, and an outer clamping member capable of overlapping the opposite sides of the wall strips, a screw for connecting the inner bracket to the clamping member, and means for adjusting the inner bracket relatively to the main bracket and the clamping member.

16. A support for a panel board and gutter wall-strips, comprising a pair of oppositely arranged angular brackets, one of said brackets adjustably secured to the bottom of a cabinet and engaging one corner of the panel board, the other bracket engaging the face of the panel board for holding said board against the bottom of the cabinet, each of said brackets having an angular portion extending at right angles to the bottom of the cabinet adapted to interfit with each other, a threaded perforation in one bracket, a slot in the other bracket, a screw for adjustably connecting the said brackets, and a clamping member arranged to overlap the ends of the gutter wall-strips adapted to coöperate with said brackets for holding said strips against the edges of the panel board.

17. A corner support for panel boards and gutter walls, comprising three coöperating parts, one part consisting of an L-shaped bracket arranged for adjustably securing the

support to the back of a cabinet between a corner of the cabinet and a corner of the panel board, said bracket having a groove for receiving the corner of the panel board, a second part consisting of a bracket having a foot adapted to bear upon the face of the panel board adjacent the corner, for holding the panel board from movement away from the back of the cabinet, the said bracket overlapping and supporting the spaced ends of adjacent sections of the gutter wall, a bolt piercing the two brackets for holding them rigidly interlocked, a third part consisting of a clamping member adapted to span the gap between the sections of the gutter walls, and arranged to overlap and support the opposite sides of said gutter walls, and a bolt piercing both of said brackets and also said clamping member for effecting the clamping of the gutter walls.

18. A corner support for a panel board and gutter walls, comprising a plurality of angular parts, one of said parts having a slotted base for adjustably securing the same to a cabinet, and having a corrugated portion to receive the corner of the panel board, a second part having a flange adapted to rest upon the face of the panel board and having a corrugated portion corresponding to and interlocking with the first part, and a third part adapted to overlap the ends of the gutter walls for holding said parts against the panel board.

19. An adjustable corner support for panel boards and gutter frames, comprising two brackets, one bracket adjustably mounted upon and secured to the bottom of a cabinet, and having a corrugated portion adapted to receive the corner of the panel board the other bracket having a corrugated portion fitting in the first bracket, and having an inwardly facing flange adapted to rest upon the face of the panel board, means for adjusting one bracket relatively to the other bracket and also to said panel board, a clamping member embracing the corner of the panel board inclosure for holding the gutter frame in place, and a screw for holding said clamping member in place.

20. A corner support for a panel board, comprising a bracket adjustably secured within a cabinet, and having a portion adapted to fit the corner of the panel board, a second bracket having means for engaging the face of the panel board, and having a portion for interlocking with said first mentioned bracket, and also engaging the inner face of the walls of the panel board, a clamping member adapted to engage the outer face of said walls, and means for clamping the second bracket to said clamping member, and adjustable means for securing the second bracket to the first mentioned bracket.

21. A corner support for a panel board comprising an adjustable bracket arranged between and adjacent to the ends of the walls of the panel board, inner and outer clamping members engaging with the inner and outer faces of the ends of said walls, the inner clamping member being provided with means for engaging with the face of the panel board, and means for adjustably se-

curing said inner member to the bracket and 13 also to the outer clamping member.

In testimony whereof I affix my signature in presence of two witnesses.

RAYMOND H. OLLEY.
